UNITED STATES PATENT OFFICE

FRANK T. POWERS, OF DOUGLASTON, NEW YORK

ETCHER SLIDE

Application filed September 4, 1931. Serial No. 561,131.

My invention relates to the art of etching photo-mechanical printing plates, and particularly to an improvement in device for supporting the plate during the etching operation.

The object of my invention is to provide a means for supporting the plate in the face down position in the etching machine, which does not require the clamping or holding of the plate in position within the etching machine while the etchant is being applied to the surface thereof.

It has been generally recognized in the photo-engraving industry that more uniform results may be obtained in the etching process with etching machines of the type in which the etchant is forcibly thrown against the plate being etched by means of paddle wheels, sprays or other devices if the plate is placed in a horizontal position with its face downward, and many etching machines have been built upon this principle.

The reasons for the superiority of this method of etching over the other methods in which the plate is supported either in a vertical or an inclined position, or in a horizontal, face-up position, are obvious. When the plate is supported in a vertical or substantially vertical position, and the etchant is projected or sprayed against the surface of the plate, that portion of the etchant which strikes the upper part of the plate flows down over the surface of the plate to the bottom. This stream or layer of etchant on the lower part of the plate has two objectionable actions or effects upon the etching. First, it forms a blanket on the surface of the plate, preventing the fresh etchant which is projected or sprayed against this part of the plate from reaching the surface of the plate. This blanketing action results in a different type of etching occurring on the lower part of the plate than that which takes place on the upper part of the plate where the projected etchant strikes forcibly directly on the plate, without any buffering or blanketing effect of a layer of etchant flowing over its surface.

Second, the upper and lower parts of a plate etched in this manner get different

treatments because the upper part is subjected to direct action of the forcibly projected or sprayed etchant while the lower part is largely etched by fluid flowing down over its face, with the result that in the lower part of the plate the upper side of the lines or dots are attacked more actively than the under side since the flow of the etchant is always downward. The result is that it is customary in machines of this type to frequently turn the plate to a new position in order to equalize the etching action. During the process of etching the operator must frequently stop his machine and turn the plate either 180 degrees or 90 degrees to overcome this unequal action.

In many types of machines a mechanical turning device is provided for the purpose of overcoming this uneven etching action. All such mechanical devices require clamping or otherwise fastening the plate to the support, and since the plates vary greatly in size these devices must be adjustable, and hence more or less complicated.

These clamping devices are objectionable for several reasons. They get out of order. They are cumbersome to handle. They stick and jamb. They are wet with the etching fluid and so make it necessary for the operator to protect his hands by gloves or otherwise, if the etchant is to be kept from the hands. They not infrequently work loose and permit the plate to fall into the machine, sometimes on the paddle wheel, wrecking it. They usually require screws, clamps or other devices which are difficult to construct of materials which are entirely immune to the action of the etching fluid.

The advantages of the horizontal face down position of the plate over the vertical position are that the etchant does not flow down over the plate as it does in the case of the vertical position. The etchant rebounds from the surface of the plate and no accumulation of etchant takes place on the surface of the plate and there is a minimum of etchant on the plate to interfere with the forceful projection of etching fluid against the plate. This condition results in a better

and more uniform etch over the entire surface of the plate.

When the plate is supported in a horizontal position face down, as it is in a number 5 of the etching machines heretofore in use, it is also necessary to employ some type of adjustable clamping or holding device, which will receive and hold any size of plate which it may be desired to etch, as described above.

10 My invention eliminates all these difficulties inherent in the heretofore used types of plate holders in etching machines.

15 In the accompanying drawings is shown a preferred embodiment of my invention from which variations may be made without departing from its spirit.

20 In the drawings like numbers refer to the same or similar parts and arrows indicate the direction of movement or rotation. Fig. 1 is a side view, partially in section, of the completed machine. Fig. 2 is a front view also partly in section.

25 Fig. 3 is an isometric perspective of the plate support. Fig. 4 is a section of the plate support on the line *a*—*b*. Figs. 5 and 6 are details of alternate types of supporting elements. Fig. 7 is a cross section of the supporting element shown in Fig. 6.

30 In the drawings, 1 is a tank or receptacle of material immune to the action of the etching fluid to be used. Within the tank is a paddle wheel or spray producing element, 2, of well known construction, supported on a shaft, 3, carried by bearings, 4. Within the 35 tank, 1, is placed a suitable etching fluid which will vary with the kind of material to be etched. The level of the top of the fluid in the tank is such that the tips of the paddle wheels dip into the fluid as they revolve and 40 throw it forcibly against the plate to be etched.

45 On one of the ends of the shaft, 3, are two pulleys 5 and 6. The pulley, 5, is operatively connected by belt, 7, to the pulley 8, of the electric motor, 9, or to any convenient source of power. The pulley, 6, is connected by the round belt, 10, to the pulley, 11, on the shaft, 12, of the centrifugal fan, 13, located in the hood, 14, which covers the top of the tank, 1. 50 In the upper portion of the tank, 1, is an opening, 15, through which opening a plate support, 16, slides on ways, 17, attached to the inner surface of the slides of the tank. Within the hood, 14, are positioned baffles, 18, 19 and 20, so arranged that spray from 55 the paddle wheel, 2, is completely intercepted, but allowing the free passage of air or gases from the lower to the upper portion of the hood. The plate support, 16, is constructed as shown in detail in Figs. 3 and 4. The 60 frame of the plate support is preferably rectangular in plan having an outer frame, 21, and a plurality of cross members, 22, having a thin section and having a concave or depressed profile along the upper edges. The

65 depressed profile of the upper edges of the thin cross members, 22, makes it possible to lay a plate to be etched face down on this tray without danger or possibility of any portion of the plate except its outer edges coming into contact with the supporting member, and herein lies the spirit of the invention.

70 In Fig. 4 is shown a large plate, 23, resting on its edges on the depressed upper profile of the cross members, 22, and also a small plate, 24, similarly resting. The thickness of the cross members, 22, is so small that they do not interfere to any discoverable degree with the uniformity of the etch obtained on the surface of the plate. The direction of the travel of the spray of etching fluid, as indicated by the arrows in Figs. 1 and 2, is parallel to the plane of the surfaces of the cross members, 22, and the distance or clearance under the plate between the plate and the cross members permits the etchant to act freely upon the very narrow strips of the surface of the plate, which lie directly above the thin cross members.

75 Figs. 5 and 6 show two alternate forms of supports, which also embody the spirit of the invention. In Fig. 5 the cross member 25 has a V shaped, depressed upper profile, which functions in a manner similar to the curved upper profile of the cross member 22 shown in Figs. 2, 3 and 4, and will receive a plate of any size to be etched in a face-down position without any portion of the plate except the two opposite outer edges coming into 80 contact with the supporting cross members. In Fig. 6 the cross member, 26, consists of a flattened wire of suitable size and stiffness bent to a downwardly curved form, similar to the depressed upper profile of the cross members, 22. This flattened wire form of support may have a cross section similar to that shown in Fig. 7, or it may have a variety of 85 other shapes without departing from the spirit of my invention.

90 These cross member of whatever form are so spaced apart that plates of any desired size from the smallest to the largest may be safely supported thereon without danger of falling between the cross members.

95 The result is a uniformly etched surface obtained without rotating the plate or changing its position either by hand or by mechanically operated means, as has been the universal custom heretofore.

100 I thereby secure the advantages of the superior and more uniform results of the face-down position of etching, which are described above, together with the simplicity and convenience of handling and placing of the vertical position without the disadvantages of either.

105 Having described my invention and the construction of some of the preferred forms thereof, so that one skilled in the art may 110

make and use the same, I shall now state what I claim to be new and novel, and for which I pray that Letters Patent be granted.

I claim:

- 5 1. In a machine for etching photo-mechanical printing plates, the combination of a receptacle for the etchant, a spray producing means, a cover to confine the spray, and a movable plate supporting member, which is characterized by having a plurality of cross members of thin material positioned with their sides parallel to the planes of travel of the sprayed etchant and having depressed upper edges adapted to support the plates by contacting only with their opposite edges, substantially as described.
- 10 2. A plate supporting member for supporting plates in a face down position for use in a machine for etching photo-mechanical printing plates, which is characterized by having a plurality of cross members with depressed upper profile adapted to support the plates by contacting only with their opposite edges, substantially as described.
- 15 3. A plate supporting member for supporting plates in a face-down position in a machine for etching photo-mechanical printing plates, which is characterized by an outer frame to which are attached a plurality of cross members having a depressed upper profile of curved form adapted to support the plates by contacting only with their opposite edges, substantially as described.

Signed at New York city, in the county of New York, and State of New York, this 24th day of August, A. D. 1931.
